(57) **CLAIM**

The ornamental design for a reel for metal wire, as shown and described.

DESCRIPTION

FIG. 1 : Perspective view 1

FIG. 2 : Perspective view 2

FIG. 3 : Partial enlarged perspective view of FIG. 2

FIG. 4 : Front

FIG. 5 : Back

FIG. 6 : Top

FIG. 7 : Bottom

FIG. 8 : Left

FIG. 9 : Right

FIG. 10 : Perspective

FIG. 11 : Partial enlarged perspective view of FIG. 10

FIG. 12 : Front

FIG. 13 : Back

FIG. 14 : Top

FIG. 15 : Bottom

FIG. 16 : Left; and,

FIG. 17 : Right

The thin lines in the representations represent contours only and do not illustrate an ornamentation or decoration on the surface of the product.
